UNITED STATES PATENT OFFICE.

LOUIS KYSER AND ALFRED C. REX, OF PHILADELPHIA, PENNSYLVANIA.

DESIGN FOR A TOY MONEY-BOX.

SPECIFICATION forming part of Design No. 12,044, dated November 30, 1880.

Application filed July 2, 1880. Term of patent 3½ years.

To all whom it may concern:

Be it known that we, LOUIS KYSER and ALFRED C. REX, both of the city and county of Philadelphia, and State of Pennsylvania, have invented an Improvement in Design for 5 a Toy Money-Box, of which the following is a specification.

Our invention relates to the design given to toy money-boxes; and it consists in the design shown in the accompanying drawings and hereinafter described and claimed.

In the drawings, Figure 1 is an elevation of our improved design for toy money-boxes. Fig. 2 is a plan of same.

15 A is the body of the box, and is composed of two curved sides, one of which may be plain, but preferably both are ornamented alike, as shown in Fig. 1.

The body A is provided with a representation of a door in the middle with the word 20 "Bank" above it, and on either side of said door are perforations, rectangular and club-shaped openings. We do not confine ourselves to the particular shape of these openings. This body A rests upon a bed-plate, B, 25 of similar elliptical shape, and secured to the top of the body is a cap, C, of similar shape to bed-plate B. This cap C is provided with slot E, through which the money to be deposited is placed, and a dome, D, having heart or other shaped openings therein, and the whole being mounted with a knob.

We do not claim anything shown in the design for toy money-box patented by us 35 August 10, 1880, for in that case the cross-section of the body was hexagonal in shape, and in this case it is elliptical.

Having now described our improved design, what we claim as new, and desire to secure by Letters Patent, is—

1. The design for a toy money-box the body of which is in shape a cylinder with an elliptical base, the sides being perforated and provided with representations of doors, substantially as shown and described.

2. The design for a toy money-box composed of cylindrical body A, having an elliptical base, bed-plate B, elliptical cap, C, provided with slot E, elliptical dome D, and ornamental perforations, substantially as shown 50 and described.

3. The design for a toy money-box having the body in shape like a cylinder having an elliptical base and surmounted with an elliptical dome, the body and dome being provided 55 with perforations, substantially as shown and described.

In testimony of which invention we hereunto set our hands.

LOUIS KYSER.
ALFRED C. REX.
